UNITED STATES PATENT OFFICE.

SIMON LAKE, OF BRIDGEPORT, CONNECTICUT.

SUBMARINE VESSEL.

No. 803,173.

Specification of Letters Patent.

Patented Oct. 31, 1905.

Application filed February 17, 1905. Serial No. 246,154.

To all whom it may concern:

Be it known that I, SIMON LAKE, a citizen of the United States, residing at Bridgeport, in the county of Fairfield and State of Connecticut, have invented certain new and useful Improvements in Submarine Vessels, of which the following is a specification, reference being had therein to the accompanying drawings.

10 This invention has for its object to secure in the construction of submarine boats greater fore-and-aft stability than has been practicable heretofore in vessels of this class.

According to the present improvement, the 15 pressure-resisting hull of the vessel is provided with a buoyant deck, preferably spaced materially above the same, and therefore affording in respect of the center of gravity of the hull a moment of considerable magnitude tending

20 to maintain the vessel upon an even keel, particularly during the operation of submersion, when the centers of gravity and buoyancy approach each other somewhat under the changing conditions occurring in the course of such

25 operation. To insure a comparatively large displacement for the upper portion of the vessel, not only is the deck preferably constructed of wood planking suitably calked to insure against penetration of water, but the sides 30 of the superstructure are made of like material, thus providing an entire superstructure of buoyant material and preferably of buoyant construction.

In the preferred form of the improvement 35 the deck, which may form the top of the superstructure, comprises, first, a course of heavy transverse planking resting upon but extending beyond the upper edges of the side walls of the superstructure to provide lateral 40 guards or guide-planes along nearly the whole length of the vessel for maintaining its direction when in motion under submersion, and upon this foundation-course is secured a second course of longitudinal planking with an 45 intermediate packing formed of a strong flexible fabric, such as canvas, coated or saturated with an impervious or waterproof substance, such as paint or paraffin, the joints intermediate the planking being properly calked to 50 exclude water. Above the courses described are laid transverse and longitudinal courses with interposed sheets of canvas coated with an impervious substance, these courses being arched and suitably supported intermediate 55 the edges to provide an interspace which may be left vacant or may inclose blocks of cork

or some other filling of light material, the upper and lower canvas sheets being overlapped at the edges and secured firmly together by a clamping-strip serving to seal 60 from penetration of water the space intermediate the courses of planking inclosing such impervious packing-sheets.

The vessel may be provided with any usual or suitable means for introducing and expelling water ballast to and from the ballast-tanks in the lower portion of the pressure-resisting hull and is preferably provided in addition with a depending solid ballast-weight capable of being shifted both vertically and 70 longitudinally for purposes to be hereinafter described, such weight serving to lower the resultant center of gravity of the entire structure below the center of buoyancy under conditions of submersion.

75 The invention will be more fully understood by reference to the drawings annexed, in which—

Figure 1 is a side elevation of a vessel constructed in accordance with the present invention, a portion of the walls amidship being broken out to expose the internal construction and arrangement of certain parts. Fig. 2 is a transverse section, upon a larger scale, on line $\alpha\alpha$ of Fig. 1 looking rearwardly; 80 Fig. 3, a partial sectional plan on line $\gamma\gamma$ of Fig. 2, representing the amidship portion of the vessel. Fig. 4 is a detail plan view representing, upon an enlarged scale, the construction of the deck of the superstructure. 85 Fig. 5 is a detail sectional view representing the outboard discharge-pipe from the pump with its check-valve; Fig. 6, a detail sectional view representing the form of check-valve employed intermediate the water-ballast tanks, 90 and Fig. 7 is an enlarged cross-sectional view showing the depending ballast-weight and its hoisting mechanism.

The pressure-resisting portion 1 of the hull is or may be of the usual cylindro-conoidal 100 shape and provided with twin screw propeller-wheels 2, each carried by a suitable shaft 3, driven for surface propulsion by gasoline-engines and for submerged propulsion by electric motors deriving their power from a system of storage batteries.

105 As shown herein, the hull proper, 1, is provided with the diametrically opposite horizontal guide-planes 4, extending longitudinally thereof and secured in position by means of suitable angle-irons. Resting upon the angle-irons 5, with their outer faces substan-

tially tangential with the circular hull, are the side walls 6 of the superstructure, built up of heavy planking secured together in any well-known or suitable manner and having the intermediate joints calked to make them watertight. Resting upon the upper edges of the side walls 6 of the superstructure and the central beam 7, attached to the top of the hull 1, is a foundation-deck flooring comprising a course of transverse planks 8, somewhat overhanging the side walls, and thus forming along the upper edges of the superstructure a second pair of longitudinal guide-planes 9, the outer edges of which are housed in the wearing-irons 10. The joints between the floor-planks 8 are stopped near the opposite edges by the stop-pegs or dowel-pins 11, driven through the same into the upper edges of the side walls 6, and intermediate such pegs are calked to seal the same from penetration of water. Upon the foundation-deck planking is secured by suitable means a course of longitudinally-laid planking 12, with the joints securely calked and with an intermediate packing composed of sheets of canvas 13, coated or impregnated with paint or paraffin, a space above being inclosed by an arched double course of transverse and longitudinal planks 14 and 15, with an intermediate packing 16, similar to that already described, the upper double course of planking being secured at the edges upon the lower course 8, and supported between the edges by one or more longitudinal wooden strips 17, with the intermediate spaces unoccupied or filled with blocks of cork 18 or other light material, as indicated in Fig. 2. The edges of the sheets of packing 13 and 16 between the two double courses of planking are extended laterally over the ends of the rows of stop-pegs 11 and beyond the edges of the upper planking, and their overlapped edge portions are firmly secured together and upon the foundation-planking 8 by means of longitudinal clamping-strips 19. By these means a comparatively light and highly-buoyant superstructure is formed comprising a buoyant deck spaced materially above the hull proper of the vessel, with the intermediate space inclosed by the also buoyant side walls formed by the planking 6, which may serve to house the various supply tanks or receptacles 20 and piping 21, as described in the United States Patent No. 714,921, granted to me December 2, 1902; but it will be readily understood that the side walls may be omitted without materially impairing the effectiveness of the improvement, the buoyant deck itself affording the principal buoyant moment around the center of gravity of the structure as a center for maintaining the trim of the vessel under all conditions.

While the particular character of apparatus for manipulating the water ballast to effect the vessel's submergence and return to

the surface is not a material part of the present invention, I have represented in the accompanying drawings a preferred construction of such apparatus comprising a pair of rotary pumps 22, each driven by an electric motor 23 and having suction or inlet pipes communicating through the pipe 24, which is connected, by means of an upright pipe 25 and distributing-pipe 26, with the sea-inlet pipe 27, controlled by a gate-valve 28. The distributing-pipe 26 has the gate-valves 29 and 30, controlling its communication with the lower portion of each initial ballast-tank of the forward and after systems *a* and *b*, respectively, the mouths of said pipe within each tank being inclosed by a guard 31, open at the bottom only, so as to enable the suction induced in such pipe by one or both of said pumps to draw water from the lowest point of the tank, while excluding the air which would otherwise enter the pipe and destroy the effective action of the pump when the level of the water reached the top of the pipe.

The discharge-passage of each pump is connected with a pipe 32, extending outboard and provided with a spring-controlled check-valve 33, whose externally-threaded stem 33^a passes through a stuffing-box 33^b in the elbow fitting above the pump 22 and has a correspondingly-threaded thrust-collar 33^c, between which and the stuffing-box 33^b is interposed the surrounding spring 33^d, normally holding the valve 33 to its seat. Lateral branches 35 and 36 from the discharge-pipe 32, controlled by valves 37 and 38, lead, respectively, to the forward and after compartments of the superstructure. The suction of both pumps is also connected by a pipe having branches 39 and 40, joining the pipes 35 and 36 intermediate their controlling-valves and the superstructure and provided with controlling-valves 41 and 42, respectively.

Each tank of both systems of forward and after ballast-tanks is connected at the bottom to the adjacent tank or tanks by a passage having a check-valve 43, opening toward the primary tank of its respective system connected with the pumps 22, as before described, and at the top with the adjacent tank or tanks of its respective system through a passage having a check-valve 44 opening in the opposite direction, and the tank farthest from the primary tank of each system is provided with an upwardly-extending air-vent pipe 45, communicating with the interior of the hull 1. As shown herein, each check-valve is of well-known form, consisting merely, as represented in Fig. 6, of a disk 44, attached by a loose connection with the outer end of a swinging arm 46, hinged to suitable lugs 47 upon the valve-plate 48, provided with a suitably-faced inclined seat 49 to receive the valve-disk.

Assuming that the valves of the entire ballast system are all closed, both compartments

of the superstructure may be filled by opening the sea-valve 29 and the controlling-valves 37 and 38 of the pipes 35 and 36, when the operation of either or both of the pumps 22 causes the suction of water through the sea connection and its discharge into both said compartments through the pipes 35 and 36, the check-valve 33 having been set to resist a pressure of water sufficient to cause its introduction into the superstructure, but to readily open for overflow when the pressure increases by the entire filling of the superstructure. The valves 37 and 38 having been closed and the action of the pump arrested, the opening 15 of the gate-valves 29 and 30 permits water to enter through the sea connection 27 and distributing-pipe 26 into the primary forward and after ballast-tank, so as to fill the same before the overflow into the adjoining tanks 20 of the respective systems through the check-valves 44, the filling of which secondary tanks is followed by the similar inflow of water through check-valves 44 into the adjacent tanks of both systems. Each of the valves 25 44 is or may be provided with means, as the stop-screw 50, Fig. 6, for locking it shut to prevent positively the inflow of water into it from the adjoining section either by action of the pumping machinery or by reason of 30 the careening of the vessel, in which case a suitable air-vent similar to that of the last tank of the system may be applied to each tank for release of the air displaced from the adjacent filled tank. In restoring the buoyancy thus partially or wholly destroyed, the sea-valve 28 having previously been closed, the ballast-tanks may be pumped out by merely opening the gate-valves 29 and 30 and setting the pumps in operation, when the 35 40 water will be drawn from the primary tanks through the pipes 26, 25, and 24 to the pumps 22 and thence discharged outboard through the pipes 32, whose relief or check valves 33 are forced open for passage of the same. 45 As will be obvious, the water from each initial tank will be replaced by that flowing in through the lower check-valve 43 from the adjoining tank, the contents of which is in turn similarly replaced by that of the adjacent tank until the entire volume of water in each is replaced by a like volume of air entering from the interior of the boat through the vent-pipe 45. The ballast-tanks having been 50 thus successively emptied, the gate-valves 29 and 30 are closed and the valves 41 and 42 opened, when the continued operation of the pumps empties the two compartments of the superstructure through the connected pipes 39, 40, and 24, leading to the pumps and discharge-pipes 32 leading therefrom.

While the general arrangement of ballast-piping shown in the drawings has been adopted particularly for convenience and simplicity of illustration, it is evident that it may be 65 readily modified to suit the disposition of

other apparatus and machinery commonly employed in submarine vessels.

The ballast-weight 51 is shown supported beneath the center of gravity z of the structure by means of a pair of links 52 53, to the lower ends of which the same is pivoted, said links being suspended by pivotal pins 54 from the interior of the ballast-weight housing 55, constituting a hollow keel portion of the vessel. To control the position of the ballast-weight, the latter is connected intermediate its ends with one extremity of a cable 56, whose other end is attached to a winding-drum 57, disposed in a well in the bottom of the hull and mounted upon a shaft 58, of which one end passes through a stuffing-box into the interior of the hull and carries a worm-wheel 59, meshing with a worm 60 upon the shaft of the actuating electric motor 61. To insure the direct lead of the cable 56 from the ballast-weight 51 to the drum 57, the after supporting-link 53 is forked at its upper end and the cable led between the branches thus formed.

For traveling upon the surface the drum 57 is operated to draw the ballast-weight 51 upwardly into its housing in the keel 55; but the ballast-weight is adjusted for submergence by lowering it to its operative position beneath the center of gravity z , as before described. When the vessel is in proper trim for submergence, with only a very small margin of buoyancy, a sufficient downward inclination may be given to the bow, either by the temporary shift of its usual stern horizontal rudder or by a slight advance movement of the ballast-weight 51 forward of the center of gravity to cause the vessel to gradually descend beneath the surface of the water while in motion under the action of its propelling apparatus, and it is evident that contrary movement of the horizontal rudder or the ballast-weight will cause the vessel to rise to the surface; but for such purpose I prefer to use ordinarily the pivoted "hydroplanes" 110 mounted in the upper guide-planes 9, as described in the United States Patent No. 650,758, granted to me May 29, 1900.

By the provision of a buoyant deck for raising the center of buoyancy and a ballast-weight depending materially below the hull for lowering the center of gravity of the structure under conditions of submergence it will be observed that I am enabled to greatly increase the fore-and-aft stability of that class 120 of submarine vessels exemplified in my said Patent No. 650,758, in which the descent and ascent in respect of the surface of the water are effected upon an even keel, and the vessel is thus rendered much more effective for actual 125 service conditions than heretofore.

While I have shown and described herein a practical embodiment of the present invention, it is to be understood that the improvement is susceptible of embodiment in struc- 130

tures differing widely in constructive details, and the invention is not, therefore, to be understood as being limited to the specific features of construction herein shown and described.

As the present improvement is specially designed for embodiment in submarine vessels, wherein the proportion of the length to the breadth of beam greatly exceeds that heretofore permissible for this class of vessels, it will be observed that the proportions represented in the drawings have been adopted merely for purposes of illustration of the various features represented, the relative length being in practice much greater than that indicated for the same breadth of beam.

While all of the various constructive features shown in detail herein are of my invention, I have not claimed certain of them in the present application, as they form the subjects of other applications filed simultaneously herewith.

Having thus set forth the nature of the invention, what I claim herein is—

25 1. A submarine boat constructed with a hull comprising a pressure-resisting body and a permanently-buoyant deck, and means for producing the submergence of the same.

30 2. A submarine boat constructed with a hull comprising a pressure-resisting body, a superposed buoyant deck, and an intermediate superstructure, and means for effecting the submergence of the same.

35 3. A submarine boat constructed with a hull comprising a pressure-resisting body, a superposed permanently-buoyant deck, and an intermediate superstructure, and means for introducing water ballast for overcoming the buoyancy of said hull.

40 4. A submarine boat constructed with a hull comprising a normally buoyant pressure-resisting body and a buoyant deck with a water-space intermediate the same, and means for effecting the submergence of the boat.

45 5. A submarine boat constructed with a hull comprising a normally buoyant pressure-resisting body and a buoyant deck with a closed water-space intermediate the same, and means for effecting the submergence of the boat.

50 6. A submarine boat constructed with a hull comprising a normally buoyant pressure-resisting body and a superposed deck formed of buoyant material, and means for effecting the submergence of the same.

55 7. A submarine boat constructed with a hull

comprising a normally buoyant closed pressure-resisting body and a buoyant deck connected to but spaced above the same, and means for effecting the submergence of the same.

8. A submarine boat constructed with a hull 60 comprising a normally buoyant pressure-resisting body and a superstructure having sides and top of buoyant material, and water-ballast means for controlling the buoyancy of the hull.

65 9. A submarine boat constructed with a hull comprising a normally buoyant pressure-resisting body and a buoyant deck formed with spaced floor-courses inclosing a hermetically-sealed space.

70 10. A submarine boat constructed with a hull comprising a normally buoyant pressure-resisting body and a buoyant deck formed with spaced floor-courses inclosing a hermetically-sealed space containing a filling of buoyant material.

75 11. A submarine boat constructed with a hull comprising a normally buoyant pressure-resisting body and a buoyant deck formed with spaced double layers of flooring with interposed sheets of material impervious to moisture.

80 12. A submarine boat constructed with a hull comprising a normally buoyant pressure-resisting body and a buoyant deck formed with spaced double layers of flooring with interposed sheets of packing united at the edges by means of clamping-strips secured to the foundation layer of said flooring.

85 13. A submarine boat constructed with a hull comprising a normally buoyant pressure-resisting body and a buoyant deck formed with spaced double layers of flooring with interposed packing composed of canvas coated with a suitable waterproof substance.

90 14. A submarine boat constructed with a hull comprising a normally buoyant pressure-resisting body and a buoyant deck having its center of buoyancy above that of the said pressure-resisting body, and a ballast-weight 100 depending beneath the center of gravity of the said body.

In testimony whereof I have signed my name to this specification in the presence of two subscribing witnesses.
